(57) **CLAIM**

The ornamental design for a collectible chip, as shown and described.

DESCRIPTION

FIG. 1 is a front perspective view of the collectible chip showing the new design;

FIG. 2 is a top view thereof, the bottom view being a mirror image thereof;

FIG. 3 is a rear view thereof;

FIG. 4 is a front view thereof;

FIG. 5 is a left side elevational view thereof; the right side elevational view being a mirror image thereof; and,

FIG. 6 is an environmental perspective view of the collectible chip in a display device; the display device being shown in broken lines and forming no part of the claimed invention.
